(57) **CLAIM**

An ornamental design for a sensor pack, as shown and described.

DESCRIPTION

FIG. 1 is an isometric view of a sensor pack, in accordance with the present invention;

FIG. 2 is a front view of the sensor pack of FIG. 1;

FIG. 3 is a rear view of the sensor pack of FIG. 1;

FIG. 4 is a right-side view of the sensor pack of FIG. 1;

FIG. 5 is a left-side view of the sensor pack of FIG. 1;

FIG. 6 is a top view of the sensor pack of FIG. 1; and

FIG. 7 is a bottom view of the sensor pack of FIG. 1.

In the drawings of FIGS. 1 through 7, the broken lines illustrate unclaimed subject matter that forms no part of the claimed design.

FIG. 8 is an isometric view of the sensor pack of FIG. 1 attached to a vehicle, in accordance with the present invention;

FIG. 9 is a front view of the sensor pack of FIGS. 1 and 8;

FIG. 10 is a rear view of the sensor pack of FIGS. 1 and 8;

FIG. 11 is a left-side view of the sensor pack of FIGS. 1 and 8;

FIG. 12 is a right-side view of the sensor pack of FIGS. 1 and 8;

FIG. 13 is a top view of the sensor pack of FIGS. 1 and 8; and,

FIG. 14 is a bottom view of the sensor pack of FIGS. 1 and 8.

In the drawings of FIGS. 8 through 14, the broken lines illustrate environment and form no part of the claimed design.

1 Claim, 8 Drawing Sheets
